UNITED STATES PATENT OFFICE.

JOHN E. BERRY, OF MONONGAHELA, PENNSYLVANIA.

GLASS-FURNACE.

SPECIFICATION forming part of Letters Patent No. 767,373, dated August 16, 1904.

Application filed March 24, 1904. Serial No. 199,680. (No model.)

To all whom it may concern:

Be it known that I, JOHN E. BERRY, a citizen of the United States, residing at Monongahela, in the county of Washington and State 5 of Pennsylvania, have invented certain new and useful Improvements in Glass-Furnaces; and I do declare the following to be a full, clear, and exact description of the invention, such as will enable others skilled in the art to which it 10 appertains to make and use the same, reference being had to the accompanying drawings, and to the figures of reference marked thereon, which form a part of this specification.

The object of my invention is an improved 15 form of glass-melting furnace to be operated in conjunction with a blowing device used in the manufacture of plate, window, or cathedral glass.

In the accompanying drawings, in two 20 sheets, forming a part of this specification, I have illustrated my invention by several views, in which—

Figure 1 is a longitudinal section of the furnace. Fig. 2 is a top sectional plan view of 25 the same, taken on the line 2 2 of Fig. 1. Fig. 3 is a longitudinal side elevation of my furnace. Fig. 4 is a cross-sectional view of the gathering-chamber and heating device, taken on the line 4 4 of Fig. 2. Fig. 5 is a cross- 30 sectional view of the channel-passage and heating device, taken on the line 5 5 of Fig. 2. Fig. 6 is a sectional view of one of the blocks used around the gathering-chamber, taken on the line 6 6 of Fig. 7. Fig. 7 is a face view 35 of the same. Fig. 8 is a side view of a series of blocks forming the walls surrounding the channel-passage. Fig. 9 is a sectional view of one of the blocks used in forming the walls 40 surrounding the channel-passage, taken on the line 9 9 of Fig. 8.

In the drawings numerals of reference designate like parts throughout the several views.

The numeral 1 is an ordinarily-constructed 45 furnace having the tank or melting-chamber 2 and working openings 3 and 3' therein.

4 is a stopper at the inner end of the channel 6 and adjustable through the opening 3. Leading at right angles from the melting-furnace is a heating-chamber 5, in the center 50 of which is a channel or inclosed passage 6,

through which the melted glass from the furnace is carried to the gathering or drawing chamber 7, located at the farther end of the channel 6.

5' represents the outer walls of the chamber 5.

8 are two combustion-chambers, one above the other, formed by the blocks surrounding the gathering-chamber 7.

9 are gas-burners introduced through the 60 blocks forming the outer walls of the chambers 5 and 8 8, a single series of burners being used at the side of the chamber 5 and so placed as to play direct against the sides of the channel 6, while a double series of burners are employed at the wider end surrounding the gathering-chamber 7, as seen in Fig. 3. 65

9' is a pipe supplying the burners with gas. Communication is had with the combustion-chambers 5 and 8 8 to the draft-stack 10, located near the melting-chamber. 70

11 represents one of the clay-block sections used in forming the heating-chambers surrounding the gathering-chamber 7. 12 12 are openings therein for the introduction of 75 the gas-burners 9.

13 is one of the clay-block sections used in forming the walls of the heating-chamber 5, having an opening 14 therein for the introduction of the burner 9. 80

The glass being thoroughly melted in the chamber 2, the stopper 4 is removed through the opening 3, when the molten glass will flow through the channel 6 into the gathering or drawing chamber 7 and will be kept in a 85 heated or workable state by heat generated in the chambers 5 and 8 8 from gas introduced therein.

The walls of my furnace, including those surrounding the channel-way 6 and gathering-chamber 7, will be made of the usual refractory material. 90

Having thus fully shown and described my invention, what I claim as new, and desire to secure by Letters Patent, is— 95

1. In a glass-furnace, a melting-chamber, a central way or channel leading from said chamber, a drawing-chamber formed at one end of said channel-way, a heating-chamber surrounding the channel, double heating-cham- 100

bers surrounding the drawing-chamber, means extending through the walls of the said double chambers and heating-chamber for introducing gas thereto, and a communicating flue 5 formed near the melting-chamber, substantially as set forth.

2. In a glass-furnace, the combination with a melting-chamber of the channel-way 6 communicating with a gathering or drawing chamber 7 formed at the far end thereof; the heating-chamber 5 formed in block-sections surrounding the channel 6; the double heating-chambers formed in the block-sections sur-

rounding the gathering or drawing chamber 7, means of introducing gas to the chambers 15 5 and 8 through the block-sections and a communicating flue 10 formed near the furnace proper; substantially as described and shown.

In testimony whereof I affix my signature in 20 presence of two witnesses.

JOHN E. BERRY.
